UNITED STATES PATENT OFFICE.

EMMA V. HALLETT, OF HARTFORD, CONNECTICUT.

DESIGN FOR A SPOON, &c.

SPECIFICATION forming part of Design No. 20,687, dated April 21, 1891.

Application filed March 18, 1891. Serial No. 385,551. Term of patent 3½ years.

To all whom it may concern:

Be it known that I, EMMA V. HALLETT, a citizen of the United States, residing at Hartford, in the county of Hartford and State of Connecticut, have invented certain new and original Improvements in Designs for Spoons, Forks, and the Like, of which the following is a full, clear, and exact specification, reference being had to the accompanying drawing, forming 10 a part thereof, where the figure is a plan view of a spoon illustrating my design.

The invention relates to the surface ornamentation of tea, coffee, sugar, orange, and the other classes of spoons and forks and similar table articles having various configurations, and the object is to provide for such articles an ornamental and aesthetic pattern which will be unique and locally characteristic.

20 The leading feature of my design resides in

the representation of a somewhat tall building having radiations extending from a portion near the top occupying more or less of the enlarged or swelled portion *a* of the handle of the article to which the design is applied. 25 In connection with the representation of the windmill is a bunch of grasses or flowers, and upon the narrow stem *b* are placed a number of characters. In the bowl *c* of the spoon at the base of the stem of the handle is the upper part or bust of a man clothed in the dress of the era of the building represented upon the handle.

What I claim is—

The design for a spoon or the like herein 35 described and shown.

EMMA V. HALLETT.
